UNITED STATES PATENT OFFICE.

ALOYS WHITE, OF NEW HAVEN, CONNECTICUT.

MUSICAL INSTRUMENT.

Specification of Letters Patent No. 28,224, dated May 8, 1860.

To all whom it may concern:

Be it known that I, ALOYS WHITE, of the city and county of New Haven and State of Connecticut, have invented a new Musical 5 Instrument; and I do hereby declare that the following is a full, clear, and exact description of the same, reference being had to the accompanying drawings, forming part of this specification, in which—

10 Figure 1 is a transverse vertical section of my instrument exhibiting one playing key and its appendages. Fig. 2 is a transverse vertical section at right angles to Fig. 1.

15 Similar letters of reference indicate corresponding parts in both figures.

My invention consists in a musical instrument composed of a series of metal springs such as are used to produce the musical sounds in what are known as musical boxes 20 attached to a sound board and a series of finger keys and suitable mechanism in connection therewith for playing upon the said springs.

25 To enable others skilled in the art to make and use my invention I will proceed to describe its construction and operation.

A represents the framing or case of the instrument.

B is a flat sound board of wood extending 30 the whole length of the instrument and having secured to it a wooden bridge a, to which the metal springs b, are attached, the said springs being arranged side by side with their vibrating ends toward the rear of the 35 instrument.

C, is the key which is supposed to be one of a series in a key board like that of a piano-forte, organ or melodion, arranged some distance below the sound board.

40 e, is the pin upon which the key works in the same manner as the key of a piano-forte or melodion.

In the rear portion of the lever there is a 45 vertical slot d, through which passes the fly lever D, and the fly E. The fly lever D, is hinged at e, to the top of the key. The fly E, is attached to the fly lever D, near the bottom by means of a screw f, and adjusted relatively to the said lever by means of a 50 regulating screw p, which screws through the said lever and presses the fly more or less away from the said lever. The lower part of the fly lever is turned back in a curved

form as shown at h, under a stationary curved ledge g, which extends all along the 55 case, and above the curved portion h, is a notch i.

F, is what may be from its action termed a let off lever attached to the case by a hinge j, at its front end and having a slot l in its 60 rear part through which the lower part of the fly lever works.

g, is a spring attached to the frame and pressing on the top of the lever F, and holding it down on the top of the ledge g, when 65 the key is at rest.

h is a spring attached to the key behind the fly lever and pressing forward the upper part of said lever and throwing back the lower portion thereof. The rear end of this 70 slot l, in the lever F, constitutes a stop to the fly lever and limits the action of the spring h, when the key is at rest.

G, is the damper attached at its rear end by a hinge m, to the back part of the case of 75 the instrument and having a pad n, on its under side to press on the spring b.

H, is a screw screwed into the top of the fly-lever D, for the purpose of raising the damper from the spring b, before the latter 80 is touched by the fly in playing.

The depression of the front end of the key by a finger in playing is accompanied by the rise of its rear end with the attached fly lever and fly. As the fly lever rises, its screw 85 H, comes into operation under the damper and raises it from the spring b, and the fly is brought into contact with the said spring. The fly lever in rising has its curved rear portion h, brought into contact with the ledge 90 g, by which its lower part is caused to swing forward thus causing its upper part and the fly to swing backward and causing the latter to draw along the spring b, toward the point a vibrating rear end thereof. In the rise of 95 the fly lever the lever F, is raised by the bottom of the notch i, coming in contact with it, but when the fly lever has been raised to a certain point and the fly has been by the action of the part h, of the fly lever under 100 the ledge g, brought very near to the point of the spring b, the corner r, of the notch i, is caused by the continued action of h, and g, to pass the bottom edge of the slot b, and by that means the upper end of the fly lever and 105 fly are caused to swing back with increased

velocity and the fly caused to pass the end of the spring *b*, very suddenly, and as the said spring has been strained upward, it, when thus liberated is caused to vibrate actively and produce the musical tone it represents in the scale, when the front end of the key is liberated from the finger the rear portion drops burying down with it the fly lever and fly and letting the damper fall on the spring *b*, to stop its vibration. In the descent of the fly lever, its upper part is held back to clear the spring *b*, by means of the lever *F*, which remains below the corner *r*, of the notch *i*, till it, in descending with the fly lever drops on to the ledge *g*, when the continued descent of the fly lever carries the corner *r*, below the said lever *F*, and allows the rear portion of the fly lever to fall back and its upper part to swing forward to a position for operating on the spring *b*, when the key is again depressed.

What I claim as my invention and desire to secure by Letters Patent is—

1. A musical instrument composed of a series of springs *b*, attached to a sound board and a series of keys and suitable mechanism in combination therewith for playing upon the said springs. 25

2. I also claim the fly lever *D*, fly *E*, and let off lever *F*, applied in combination with each other and with the key *C*, and stationary ledge *g*, to operate substantially as herein described. 30

3. And I further claim the arrangement of the damper in combination with the spring *b*, and the fly lever *D*, substantially as herein described. 35

ALOYS WHITE.
